FIG 111.

FIG 11.

Des. 686

Garrettson Smith, Henry Brown, and
Julius Holzer of Philadelphia, Penna.

Assignors to

I. G. Abbott, and A. Lawrence, of same place

Letters Patent No 686 Dated Jan 20th 1855. Antedated Oct 30th 1852

The schedule referred to in these Letters Patent, and making part of the same. —

To all whom it may concern:

Be it known that we Garrettson Smith, Henry Brown, and Julius Holzer, of City of Philadelphia, and State of Pennsylvania, have produced a new & original Stove Design, called the "Fanny Fern," and we do hereby declare, that the following is a full, clear, and exact description of the same, reference being had to the annexed drawing forming part of this specification, in which

Figure 1. is a front elevation —

Figure 2. is a side elevation — and

Figure 3. is a top view of the stove. —

Similar characters of reference in the several figures denote the same part of stove and design. —

The front plate A. bears the feed door B. and draught door C. The former raised above the plate by the moulding a. and ornamented by the foliage b. and scrolls c. arranged and configured, as shown in figure 1. so as to form an open work panel to the door. —

The door C. has a rim d. bearing projections e. and is ornamented in bas-relief by the sweeping foliage f. arranged and having the configuration set forth in figure 1. —

Upon the plate A. and above the door B. is the foliage h. connected by the twisted beads i. with the ornament P. situated between the doors B. and C. and composed of foliage arranged, and having the configuration set forth in the above named figure. On the plate A. below the door B. is the inscription "Fanny Fern" in raised capitals. —

On side plate E, is ornamented in bas-relief by the band of foliage L, arranged and configured, as shown in figure 2. The left plate H, is surrounded with a moulding M, and has above the moulding the band of foliage N, configured and arranged as set forth in the drawing. The base plate R, has on its edge the moulding P, made up as shown in the drawing.

What we claim as our invention or production, and desire to secure by Letters Patent, is

The design, configuration, and arrangement of the ornaments in bas-relief, of the stove "Fanny Fern," as set forth in the specification & the annexed drawings.

In testimony whereof we have hereunto signed our names before

two subscribing witnesses.—
